By his Attorney, J. H. Brown

UNITED STATES PATENT OFFICE.

JOSEPH M. FLANNERY, OF BRADDOCK, PENNSYLVANIA.

SKIRT-SUPPORTER.

SPECIFICATION forming part of Letters Patent No. 644,903, dated March 6, 1900.

Application filed June 3, 1897. Serial No. 639,197. (No model.)

To all whom it may concern:

Be it known that I, JOSEPH M. FLANNERY, a citizen of the United States, residing at Brad-
dock, in the county of Allegheny and State of
Pennsylvania, have invented certain new and
useful Improvements in Skirt-Supports; and
I do hereby declare the following to be a full,
clear, and exact description of the invention,
such as will enable others skilled in the art to
10 which it pertains to make and use the same,
reference being had to the accompanying
drawings, which form a part of this specifica-
tion, in which—

Figure 1 indicates a perspective view of my
15 improved skirt-supporter. Fig. 2 is a sec-
tional view of the same. Figs. 3 and 4 are de-
tails of modification of the same. Fig. 5 is a
front elevation of the end of the skirt-band.

My invention relates to devices adapted to
20 be secured around the waist and to support
the skirt, my object being to produce a device
of this general character to which the rear of
the skirt may be attached at different points
and then adjusted properly by the slideable ex-
25 tension upon the flexible band; and to this
purpose it consists of the novel construction
and arrangement of parts hereinafter specific-
ally described, reference being had to the
30 accompanying drawings, forming part hereof,
in which like letters and numerals indicate
like parts wherever they occur.

Referring to said drawings, 1 is a flexible
band adapted to be secured around the waist,
one end of the same being provided with a se-
35 ries of eyelet-holes *a a* and the other end with
a headed pin *b*, adapted to engage in said eye-
let-holes for this purpose. A slideable keeper
c is adapted to maintain the said ends in close
40 contact. 2 is a plate slidably mounted upon
said band, the edge of said plate projecting
or extending above the body of the band and
having formed therein a number of vertically-
disposed slots *d*, the middle slot being of

greater depth or length than the remaining
slots and the said slots being adapted to re- 45
ceive buttons or other fasteners secured upon
the band of the skirt or, as shown in Figs. 3
and 4, with buttons *e e*, secured on the outer
edges of the same to engage in holes in the
ends of the skirt-band *f*, which may be, as 50
shown in Fig. 5, provided with an enlarged
piece *g*, preferably formed of leather.

Having described my invention, what I
claim, and desire to secure by Letters Patent,
is—

55

1. A skirt-supporter comprising a flexible
band in one end of which is formed a series
of eyelet-holes and the opposite end being pro-
vided with a headed pin adapted to engage
said eyelet-holes, a slideable plate mounted on 60
said band the upper edge of which projects or
extends above the upper edge of the body of
the band and in which is formed a number of
vertical slots forming seats to engage fasteners
on the band of the skirt, substantially as 65
set forth.

2. A skirt-supporter comprising a flexible
band in one end of which is formed a series
of eyelet-holes the opposite end being pro-
vided with a headed pin adapted to engage
said eyelet-holes, a slideable plate mounted on 70
said band the upper edge of which projects or
extends above the upper edge of the body of
the band in which are formed vertically-dis-
posed slots the middle slot being of greater
75 length or depth than the remaining slots, the
said slots forming seats to engage fasteners
on the band of the skirt, substantially as set
forth.

In testimony that I claim the foregoing I 80
hereunto affix my signature this 31st day of
May, A. D. 1897.

JOSEPH M. FLANNERY. [L. S.]
In presence of—

GEO. B. PARKER,
WILLIAM J. BROWN.
